UNITED STATES PATENT OFFICE.

JOSEPH A. COYLE, OF BALTIMORE, MARYLAND.

RUBBER FOR REMOVING MARKS FROM PAPER.

1,170,220.

Specification of Letters Patent.

Patented Feb. 1, 1916.

Application filed October 14, 1915. Serial No. 55,774.

To all whom it may concern:

Be it known that I, JOSEPH A. COYLE, a citizen of the United States, residing at Baltimore, in the State of Maryland, have invented certain new and useful Improvements in Rubbers for Removing Marks from Paper, of which the following is a specification.

This invention relates to an elastic ink-eraser having a novel laterally-projecting clip device.

One object of this invention is to improve rubbers used for erasing and removing ink marks from the surface of paper, by providing such rubbers with spring clip arms which project from the rubber to serve two useful purposes, namely, first, to grasp onto some stationary part of a desk or type-writing machine and thereby hold the said rubber eraser in a fixed position until it may be wanted for erasing, and second, to serve as a handle for the said rubber which handle a person's hand may grasp to facilitate the operation of applying the eraser to the surface of paper.

The invention is illustrated in the accompanying drawing, in which,—

Figure 1, is a perspective view of the article consisting of a combined ink-eraser and laterally-projecting clip. Fig. 2, is a view of the flat blank from which the spring clip is formed. Fig. 3, shows the flat rubber or eraser block with the two arms of the spring clip partly attached thereto. Fig. 4, is a section view of the eraser block and clip devices, as a finished article.

Referring to the drawing, the eraser block 5, may be of any well known material now used for removing pencil marks or ink marks from the surface of paper, and this block may have any preferred shape; in the present instance it is a flat relatively thin block; it is provided with a center hole 6, and also with a second hole or slot 7, located in the block intermediate of the center and the rim-edge 8. The spring-clip may be first formed of the shape substantially as shown in Fig. 2, from some suitable sheet material, such as metal, celluloid, etc.; this blank is intended to be folded on a crosswise central line 9, so as to bring the two arms 10,

together, as seen in Figs. 1 and 4. The blank as shown in Fig. 2, has an open slot 11, at one side of the said central folding line 9, and at the opposite side thereof has 55 a tongue 12, which may be formed in the material of the blank by a suitable die and punch that will cut only three sides of a rectangular hole 13, see Figs. 2 and 4, leaving the fourth side uncut; this tongue as 60 seen in Figs. 2 and 3, is to be bent as shown in Figs. 1 and 4.

When the blank shown in Fig. 2, has been bent or folded at said central line, one arm 10, of the blank may be inserted into and 65 passed through the central hole 6, in the eraser block, as seen in Fig. 3; the tongue 12, on one arm of the clip should extend through the hole 7, in the rubber, and also through the slot 11, in the other arm 10, and 70 the end of the tongue 12, must be finally bent at a right angle, as shown in Figs. 1 and 4, to lock the clip parts together. It will be seen the two clip arms 10, are secured to the eraser block 5. The oppositely-curved 75 conformation of the ends of the two arms 10, facilitates slipping the two arms onto some stationary part of a desk or other structure so that the clip-arms will retain the rubber block 5, in some convenient place until it 80 may be wanted for the purpose of erasing.

In the present instance the locking of the two clip arms onto the eraser block 5, is effected by a tongue 12, bent at right angles 85 and being integral with one of the clip arms, but the invention is not limited to the use of this particular lock device.

It will be understood the laterally-projecting arms 10, of the clip device may be 90 grasped by the thumb and fingers of a person's hand as an ordinary handle might be grasped and thereby the eraser can be much more firmly held while the operation of rubbing is going on to erase a mark.

Having described my invention what I 95 claim is,—

1. The combination of a block of erasing material provided with a hole, and a spring clip of sheet material having two arms one of which has passed through said hole and 100 also having a tongue that locks the two arms and block together.

2. The combination with an elastic body having a slot in its center, of a pair of jaws comprising a strip of sheet-material bent and folded at its center—the center part 5 fitted into the said slot and one jaw being at one side of the body and the other jaw at the opposite side and the free ends of the jaws being parallel with each other and both jaws

extending laterally from the said body and forming a spring clip.

In testimony whereof I affix my signature in the presence of two witnesses.

JOSEPH A. COYLE.
